UNITED STATES PATENT OFFICE

172,357

COMBINED NUT OPENER AND HOLDER

Alfred N. Nelson, Flushing, N. Y.

Application January 21, 1954, Serial No. 28,614

Term of patent 14 years

(Cl. D44—1)

To all whom it may concern:

Be it known that I, Alfred N. Nelson, a citizen of the United States, a resident of Flushing, county of Queens, State of New York, have invented a new, original, and ornamental Design for a Combined Nut Opener and Holder, of which the following is a specification, reference being had to the accompanying drawing, forming a part hereof.

Figure 1 is a perspective view of the combined nut opener and holder showing my new design; Fig. 2 is a side elevational view thereof;

Fig. 3 is a cross-sectional view thereof taken along the line 3—3 of Fig. 1.

I claim:

The ornamental design for a combined nut opener and holder, as shown.
